UNITED STATES PATENT OFFICE.

DAVID LARSON, OF BERLIN, GERMANY, ASSIGNEE TO OTIS ELEVATOR COMPANY, OF JERSEY CITY, NEW JERSEY, A CORPORATION OF NEW JERSEY.

ELEVATOR-CONTROL SYSTEM.

1,225,976.

Specification of Letters Patent. Patented May 15, 1917.

Application filed July 30, 1912. Serial No. 712,341.

To all whom it may concern:

Be it known that I, DAVID LARSON, a subject of the King of Sweden, residing at Berlin, in the Province of Brandenburg and 5 Kingdom of Prussia, Germany, have invented a new and useful Improvement in Elevator-Control Systems, of which the following in a specification.

My invention relates to elevator control systems, and more particularly to a system of control for automatic alternating current electric elevators.

One of the objects of my invention is the provision of a simple, cheap and effective 15 system of controlling elevators, and it consists in the various features of construction and arrangement of parts having the general mode of operation substantially as hereinafter more particularly set forth.

20 Referring to the accompanying drawing, wherein I have illustrated diagrammatically a system of control containing an embodiment of my invention, S designates a switch which connects and disconnects the system 25 of control and a source of three phase alternating current supply indicated by the conductors α , b and c . An electric motor M is connected through suitable inclosed gearing to a winding drum G about which are wound 30 the cables 1 and 2 connected to the counterbalance weight W and elevator car C, respectively. An electrically operated brake B may be arranged between the motor and the winding drum and the same operates to stop 35 the hoisting machinery every time the line current is cut off from the motor and is released when it is desired to start the elevator. The motor M is here shown as a three phase 40 motor whose rotor or secondary winding is connected through the slip rings 3 which in turn are connected to a starting resistance R. The starting resistance is normally in circuit with the rotor winding of the motor 45 when the motor is at rest but may be varied or gradually short-circuited by means of accelerating switches, 4, 5, 6 and 7 to effect the accelerating of the motor to full running speed. Three of the accelerating switches are substantially the same in construction. 50 the last one designated by 7 comprising in addition to its resistance controlling contacts a dashpot 7 which retards its closing action and an insulated contact 9 which is adapted to pass over and make contact with a series 55 of fixed contacts, 10, 11 and 12, which are

connected to the magnet windings of the accelerating switches 4, 5 and 6, respectively. The direction of rotation of the motor is controlled by means of the reversing switches U and D, which are similar in construction 30 and operate to interchange or reverse the main line connections α and c , the middle main b being connected directly to the stator winding of the motor. A circuit closing switch L controls the main line circuit to 35 the motor and the same operates only after the reversing switches have first established the proper motor connections, so that the motor will rotate in the desired direction when its circuit is closed to the main line at 40 the contacts of the switch L. The reversing switches U and D are provided with non-interference contacts, 25, 26 and 27, 28, respectively, which are always in closed circuit 45 relation when both of the switches are de- 50 energized, but will operate to prevent a false operation when the controlling system is in 55 operation. At each floor landing is a push 60 button, 29, 30, 31 and 32, also a door contact 33, the latter being closed whenever the 65 corresponding door is closed, and vice versa. The elevator car C has a series of push buttons, 34, each button corresponding to a floor 70 landing, and the car also contains a stop 75 button 35 and car gate contact 36. H designates a floor controller, and while the same 80 may be of any desired type of which there are several, I prefer to employ the one shown 85 diagrammatically on the drawing, which is similar to that shown and described in patent 90 to Carichoff, 783,174, February 21, 1905, 95 system of electrical control. This controller comprises a series of cam operated circuit controlling switches, 56 and 47, which are 100 operated by a corresponding series of rotating arms geared to some moving part of the hoisting machinery, such as the drum shaft for instance, and moving in synchronism 105 with the elevator car. Similar switches, 57 and 58 are normally closed and only operate 110 at the limits of car travel. There are floor relays, 50, 51, 52 and 53, corresponding to the push buttons in the car and at the various floor landings. There is also a non-interference magnet 37, comprising double 115 wound coils, 38 and 39, and an armature 41, carrying a pair of contacts, 42 and 43. The contact 43 is normally in electrical engagement with a fixed contact 44, while the contact 42 is adapted to engage a contact, 40, 120

when the magnet 37 is energized. A slack cable switch, 59, and limit switches, 61 and 62, are arranged toward the top and bottom of the hatchway and are operated by the 5 car when the latter overruns its normal limits of travel in either direction. A governor switch 60, normally in closed position, is shown, but which will open to interrupt the operating circuit whenever the car attains 10 an excessive speed.

Having described the parts of the apparatus, I will point out the operation of the system. Assuming the car to be at rest opposite the second floor landing, as shown, 15 let it be supposed that a passenger on the third floor landing desires to use the elevator car. Upon pushing the button 31 a circuit is established to the floor relay 52, which circuit may be traced from the main 20 *c*, through the wire 63, contacts 28 and 26 of the respective reversing switches D and U, resistance 45, contacts 43 and 44 of the non-interference magnet switch 37, wire 64, which is common to all of the floor landing 25 buttons, through the push button 31, wire 65, winding of relay 52, and by the wire 66, which is common to all of the floor relays, through the slack cable switch 59 and to the main *a*. The relay 52, with the 30 resistance 45 in series with it, is now connected across the mains *c* and *a*, and the relay will at once operate to close its contacts 54, thereby establishing a circuit through the floor controller H and the 35 magnet of the reversing switch U. This latter circuit may be traced from the main *a*, through the conductor 66, relay 52, relay contacts 54, contacts 48, 47 and 49, of the floor controller, contacts of switch 57, contacts 27, the magnet winding of the reversing switch U, wire 67, door contacts 33 in series, car gate contact 36, contacts of stop switch 35, and by the wire 68 to the main *b*. The closing of the relay contacts 54 establishes 40 a self holding circuit for this relay and for the magnet winding of the reversing switch U, and the push button 31 may now be released without interrupting this self holding circuit. The reversing switch 45 U is now energized to close its upper contacts 13 and 15, and open the lower contacts 25 and 26. The closing of the contacts 13 and 15 energizes the contacts 20 and 19, respectively, of the switch L, the 50 contact 20 being now connected to the main *a*, while the contact 19 is connected to the main *c*. Since one terminal of the magnet winding of switch L is connected to the contact 19, and this contact is now alive, a circuit 55 is established through the winding of switch L, which circuit may be traced from the main *c*, through the contacts 15 and 19, winding of the switch L, through the limit switches 62 and 61, governor switch contacts 60, to the main *b*. The switch L now

operates to close its contacts 20, 21, and 19-22, and thus close a circuit to the stator winding of the motor M, and the brake B, and the motor starts at slow speed to raise the elevator car, its speed being limited due 70 to the resistance R being in the rotor circuit at this time. Upon closing a circuit to the motor and brake, a circuit is also closed to the accelerating magnet 7 through the conductors 69 and 70, the latter conductor being common to all of the accelerating magnets 4, 5, 6 and 7. Since the accelerating magnet 7 is energized, it starts slowly to raise its core, this action being retarded by the dashpot 8, hence it will 75 take an appreciable period of time before the contact 9 engages the contact 10. When this does occur, a circuit is closed to the magnet winding of the accelerating switch 4 and the latter immediately raises its core and connected contacts into engagement with the corresponding stationary contacts directly above to short circuit a portion of the starting resistance and allow the motor to increase its speed. As the core of the 80 accelerating magnet 7 continues to rise it successively energizes the magnet windings of the accelerating switches 5 and 6 which operate in turn to short circuit additional portions of the starting resistance further to increase the speed of the motor, until finally the accelerating switch 7 has reached the limit of its movement closing its upper contacts, whereupon all of the starting resistance will be short circuited and the motor will have reached full running speed with short circuited rotor.

It will be observed that the contact 9 in passing over the stationary contacts 10, 11 and 12, makes contact with one of the contacts such as 11 before it leaves the contact 10 next to it. Thus when the accelerating magnet 7 operates, the resistance R is gradually short-circuited by the magnets 4, 5, 6 and 7, and furthermore, when the magnet 7 has reached the limit of its movement in an upward direction, the contact 9 has been carried out of engagement with all of the contacts 10, 11 and 12, and the magnet alone remains energized. This method of operation effects a considerable saving in current consumption and prevents the accelerating magnets 4, 5 and 6 from becoming overheated since they are only momentarily energized.

In order to guard against any possible interference from another floor push button, I have provided the non-interference contacts 26 and 28 on the reversing switches, and it will be observed that as soon as one of the reversing switches such as U starts to move, and before it has closed its upper contacts, the contacts 26 will be separated, and, since these contacts are in series with the common wire of the floor push buttons,

it follows that these buttons become dead or inoperative. The contacts 25 are in like manner separated upon the operation of the reversing switch U, and since they are in series with the magnet winding of the reversing switch D, it becomes apparent that it would be impossible to effect the simultaneous operation of both the reversing switches.

10 As the car approaches the designated floor landing corresponding to the location of the push button 31, the floor controller will operate to move the bridging contact 47 out of electrical engagement with the fixed contacts 48 and 49, thereby opening the self holding circuit comprising the magnet winding of the reversing switch U and floor relay 52, and the reversing switch at once becomes deenergized and opens the motor, 15 brake, and accelerating magnet circuits, and the car comes to rest adjacent the third floor landing, the starting resistance again being placed in circuit with the rotor of the motor ready for a subsequent start. It will be noted that the operating circuit of the reversing switch includes the door contacts, 20 car gage contacts and the stop button in the car; therefore it is seen that in order to start the elevator car it is absolutely essential that all of the landing doors and the car gate be in closed position, and furthermore if any one of these doors be accidentally opened while the car is in motion the latter will at once come to rest regardless 25 of its position in the hatchway. By means of the stop button 35 in the car, the car occupant may at any time stop the car by merely pressing the button.

The operation from one of the car buttons 34 is somewhat different from that of the floor buttons, since the car button operation brings into play the non-interference magnet 37. This operation may best be understood by assuming that the passenger on the 35 third floor has entered the car and, having closed the landing door and car gate behind him, operates the upper push button of the series of push buttons in the car designated by 34. A circuit may now be traced from the main c, through the resistance 46, 40 winding 38, wire 71, upper push button 34, floor relay 53, slack cable switch 59, and to the main a. The relay 53 now closes its contacts 72 which establishes a self holding 45 circuit for the relay 53 and reversing switch U including the contact 73 of the floor controller H. This self holding circuit may be traced as before, and the motor starts and accelerates to full speed automatically and 50 will automatically stop at the top floor landing without further attention from the car operator. The winding 38 of the non-interference magnet 37 is energized by the operation of the car push button and it at once 55 separates the contacts 43, 44 and closes the

contacts 40 and 42. Since the contact 43 is connected to the common wire of the floor push buttons it follows that the isolation of this contact renders all of the floor buttons dead so that no interference can be had from that source. The closing of the contacts 40 and 42 establishes a self holding circuit for the non-interference magnet 37, which circuit may be traced from the main b, stop button 35, gate contact 36, door contact 46, wire 67, contact 42, contact 40, winding 38 and 39 in series, resistance 46, and to the main c. This self holding circuit is independent of the floor controller and will remain unbroken even after the car has come 60 to rest at the top floor landing. The lower reversing switch contacts 26 and 28 insure that there can be no interference from the floor buttons when the motor circuit is closed or is being closed, while the non-interference 65 contacts 43 and 44 effect a similar result even after the car has stopped at a floor landing. In order to restore the operation to the floor buttons, the passenger in the car, having reached his destination, opens the 70 car gate and landing door and, having passed out of the car, closes the gate and door after him. Upon opening the car gate the self holding circuit of the non-interference magnet 37 is interrupted at the car 75 gate contacts and the contacts of the magnet 37 assume their normal position in which a circuit may be closed from a floor button through these contacts 43 and 44.

If the car should for any reason overrun 80 the upper floor landing the floor controller will open the switch 57 thereby interrupting the circuit of the up reversing switch magnet to stop the car, and in case the switch U failed to operate, the car would at once 85 engage the limit switch 61 which would immediately open circuit the operating magnet of the switch L and the latter would cut off the current to the motor and brake to stop the car.

It will be noted that the operating circuits involve all three phases of the main line and unless all of the phases are alive the circuit to the motor cannot be closed. For example, if the phase a is dead, the 90 floor relays 50, 51, etc., cannot be energized to effect the closure of a reversing switch. If the phase b is dead, the motor circuit closing switch L cannot be operated, and if the phase c be dead, the floor relays 50, 51, 95 etc., cannot be operated nor can a reversing switch be closed. From this it follows 100 that were any one of the phases to become ineffective or dead the motor circuit cannot be closed. This feature is an important 105 one since were it possible to close the motor on a multiphase circuit in which one of the phases were dead, the motor would operate, if at all, at greatly reduced speed and also draw a heavy current from the line which 110

would very soon overheat and damage the motor.

The operation of the system for a descending elevator car is similar to that already described, the floor controller circuits being such that the reversing switch D will be energized instead of the reversing switch U as before. The lower contacts 28 and 27 of the switch D effect the same or similar results as the contacts 26 and 25 respectively of the switch U, to prevent interference from the push buttons and to prevent the simultaneous operation of the reversing switches.

15 In connection with the non-interference magnet 37, it will be noted that it performs the double function of preventing interference from the floor buttons after a car button has been operated and the car is in motion, and also to prevent such interference even after the car has come to rest at the designated floor landing; thus after the car has come to rest the passenger must first leave the car and close the car gate and landing door after him before it is possible to obtain control of the elevator car from

the push buttons at the various floor landings.

Without limiting myself to the precise details of construction and arrangement of parts shown and described, I claim, and desire to protect by Letters Patent the following:—

In a push button controlled elevator, the combination of a polyphase supply circuit, 35 an alternating current motor, a magnet controlled reversing switch for the motor, a magnet controlled main line switch for the motor, a relay controlling the reversing switch, and a push button for operating the relay, the operating magnets of the reversing switch, main line switch and relay being connected in a different phase of the supply circuit.

In testimony whereof, I have signed my name to this specification in the presence of 45 two subscribing witnesses.

DAVID LARSON.
